UNITED STATES PATENT OFFICE

GEORGE F. EGAN, OF JERSEY CITY, NEW JERSEY

SEWER CONSTRUCTION

Refiled for abandoned application Serial No. 182,356, filed April 9, 1927. This application filed October 16, 1929. Serial No. 400,149.

- The present invention relates to sewer constructions, and more particularly refers to a construction of catch basin and cover with a receptacle suspended therein to receive sticks, stones, trash and other matter that may find their way naturally, or be thrown purposely, into catch basins; whereby the receptacle, which is removable, will hold such matter and prevent its entrance into the basin.
10. An object of the invention is to provide a sanitary construction for sewers in which the receptacle construction will not interfere with the free passage of liquids to the basin and to the sewer.
15. A further object of the invention is to provide a receptacle construction in which provision is made for the hoisting of the receptacle from the basin and the removal of the contents of the receptacle conveniently and quickly.
20. through a door or gate in the receptacle.

This application is refiled for my prior similarly entitled abandoned application filed April 9th, 1927, Serial No. 182,356.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a vertical section through a catch basin and sewer construction with a cover and receptacle embodying my invention in place and with a vehicle at the street level above;

Figure 2 is a side elevation of a receptacle embodying my invention;

Figure 3 is a vertical section of a basin and a slightly modified form of receptacle;

Figure 4 is a top plan view of a basin cover;

Figure 5 is a cross section taken on the line 5-5 of Figure 4;

Figure 6 is a bottom plan view of a receptacle and of a door at the bottom thereof;

Figure 7 is a side elevation of a further modified form of receptacle;

Figure 8 is a vertical section taken on the line 8-8 of Figure 7;

50. Figure 9 is an elevation of a receptacle

taken at substantially right angles to Figure 7, and

Figure 10 is a top plan view of the receptacle shown in Figure 8.

In the drawings, 11 designates a sewer and 12 and 13 conduits leading from the sewer to a catch basin 14. This catch basin may be wholly or partly in the street or roadway and is ordinarily provided with a perforated cover. 15 designates an annular or other frame in which a cover may fit. The frame 15 may be wholly in the street or roadway or a portion of the frame may be underneath the curb and a portion in the street or roadway. In either event that portion of the frame in which the cover is intended to fit will be so located that the cover may be removed therefrom without hindrance from the curb. The frame 15 or so much thereof as extends into the street or roadway will preferably be so mounted that when the cover is in place in the frame the outer edge of the cover will be flush with the surface of the street or roadway. The frame 15 is shown as provided with a flange 16 intended to fit in a depressed shoulder 17.

The frame 15 is shown as provided with an inner downwardly and inwardly beveled seat 18 for receiving the complementally formed external edge of a perforated disc 80 or plate 19.

The receptacle illustrated in Figure 1 is shown as comprising a cylindrical upper neck 20 adjoining the plate 19 and a lower frusto-conical body portion 21 shown as 85 tapering downwardly and as open at its lower end. The upper portion of the receptacle is shown as provided with one or more lateral openings 22 above which are located downwardly and inwardly sloping hoods 23 to prevent matter which enters the basin through the cover from falling into the openings 22.

Shown at the lower end of the receptacle and at diametrically opposite parts are plates 24 riveted or otherwise secured externally on the receptacle. Each plate 24 is shown as provided with spaced eyes 25 and 26, the openings in which are shown as in alignment to receive pins 27 and 28 by which the door 29 may be held in place.

100

The door 29 is shown as provided at each side with an eye 30 adapted to fit between the spaced eyes 25 and 26, whereby the pin may pass entirely through the three eyes. 5 Either or both pins may be provided with a head or handle 31 by which it may be withdrawn, and preferably the pins will be held as by the connections 32 to the receptacle so that on their removal danger of loss may be 10 avoided.

Either or both pins may be removable, but, if preferred, a fixed rivet or bolt may be located at one side of the door 29 on which the door may swing, while the removable pin at 15 the other side will permit of the opening of the door.

In Figure 1 a vehicle 33 is shown as standing upon the street adjacent the basin and as having a swivelly mounted boom 34 extending therefrom with a pulley wheel 35 mounted in its outer end to slidably receive a cable 36. A drum 37 is shown on the vehicle and as arranged to receive this cable. The drum may be wound and unwound either 25 by hand or appropriate machinery. The free end of the cable is shown as carrying a hook 38 adapted to engage in the upper portion of the receptacle or in the top plate 19 for the purpose of withdrawing the receptacle upwardly, whereby its contents may be 30 discharged into the vehicle 33 or into another vehicle.

To enable the contents of the receptacle to be discharged the door 29 is opened after the 35 receptacle has been swung above the vehicle 33 or above such other vehicle into which it may be desired to discharge the contents of the receptacle.

In Figures 3, 4 and 5 is shown a modification 40 in which similar parts bear the same reference numerals. The modification consists in leaving the upper end of the receptacle open and provided with an out-turned flange 39 adapted to seat within a shouldered recess 40 in a frame 41. The hook 38 is shown as so arranged as to engage an eye 42 towards which the arms 43 and 44 are shown as converging from the sides of the receptacle. These arms may be riveted or otherwise secured to the receptacle. 50

In this case a separate cover 45 is provided for the basin and receptacle. In Figure 5 a cover 45 is shown as provided with a flange 46 to fit upon the out-turned flange 39 of the receptacle. The cover 45 is also shown as provided with radially elongated slots 47 and 48 of an appropriate design leaving a solid central portion 49 which may be engaged by the hook 38. The top plate 19 of the receptacle, shown in Figure 1, may be similarly formed if desired.

Referring to Figures 7 to 10, inclusive, a further modified form of receptacle is shown. In Figures 7 to 10 four spider arms 50 are shown as provided and these spider arms are

shown as meeting at their upper ends and as provided with a perforation 51 which may receive the hook 38.

The lower portion of the receptacle shown in Figures 7 to 10 is shown as of hopper shape and as having a sloping rear wall 51, sloping side walls 52 and 53, shown in Figure 7, and an opening 54 at its front portion which opening is shown as arranged on an inclination extending at substantially right angles to the inclination of the rear wall 51. 70

The rear wall will, therefore, divert the contents of the receptacle rapidly out through the opening 54 which is normally closed by a door 55. The door 55 is shown as provided at its upper end with an elongated tongue 56 having its terminal part inserted through a slot 57 in the side of the receptacle and turned downward as indicated at 58 in Figure 8. A loose joint may be thus made upon which the door 55 may swing. When the door is closed liquid may ooze into the basin from the space between the outer wall of the receptacle and that part of the door which impinges against the outer wall of the receptacle but solid matter will not enter the basin through such space. 80

The lower portion of the door 55 is shown as provided with spaced alining eyes 59 and 60 adapted to straddle a single eye 61 on the lower end of the rear wall 51. The door may be held closed by the engagement through the eyes referred to of a pin 62 shown as having a handle 63 by which it may be withdrawn. 85

In Figures 1 and 3 are shown a ladder 64 for enabling a workman to descend into the basin 14. In these figures are also shown traps 65 extending about the mouths of the conduits 12 and 13. These traps are shown as provided with perforations 66 in their lower portions, these perforations preferably not extending above the lowermost portion 67 of the mouths of the conduits. The traps may be so hinged that they may be thrown to one side or upwards as desired, and if a trap be so hinged that it may be thrown upward such trap may rest against the wall of the basin. 90

In Figure 5 the upper surface of the cover is shown as tapered towards its middle, and the cover may be made thicker towards its middle, as is also shown in Figure 5, to impart additional strength. 100

Receiving basins are used as convenient places in which to dispose of decaying fruits and vegetables, refuse from the manufacture of wines and other liquors, rotten fish, dead animals, and even such bulky things as bedding. If such substances cannot otherwise be readily put into a basin the cover of the basin is removed, the things thrown into it, and the cover sometimes placed back into proper position and sometimes not. It may be that receiving basins are more likely to be put 110

to such uses in the less desirable sections of a community than elsewhere, but the conservation of public health demands special watchfulness in those less desirable sections. Moreover, if the cover be removed and not returned to place or if the cover be not returned to proper position passersby are exposed to the risk of injury.

It is proposed to use a cover sufficiently strong to withstand any strain to which it is likely to be subjected, and if the cover be made, as ordinarily, of iron or steel, it will be of such weight as not to be easily removed.

In Figure 1 the receptacle is shown as integral with or secured to the cover, and the receptacle, itself, will ordinarily be of considerable weight. The receptacle, itself, would have to be withdrawn a considerable distance out of the basin to gain any access whatever to the basin and it would have to be withdrawn entirely to gain complete access to the basin.

The difficulties of using a basin as a dumping place will be evident.

In the construction shown in Figures 2 and 3, to gain access to the basin the cover and receptacle would both have to be removed. It is true that after removal of the cover things might be thrown down but such things would be caught in the receptacle and not enter the basin.

At present, in cleaning basins, the cover is removed. A workman descends into the basin. Another workman standing at the surface lowers a hand bucket to the workman in the basin for filling. After a bucket is filled it is hoisted by one or more workmen to the surface and unloaded into a vehicle. If contents of a basin have become so solidified that the workman in the basin cannot readily fill buckets lowered to him he must use a pick, shovel, crowbar, or other instrument to break up the solid mass. This delays the emptying of the basin and meanwhile the time of all the men employed in connection with the emptying of the basin is wasted. The basin must be built sufficiently large to give the workman in the basin room enough to work; the breaking up of material in the basin is attended with danger of damage or injury to the sides and bottom of the basin and to the conduits leading from the basin to the sewer; should the workman or workmen whose duty it is to pull up the loaded buckets allow the rope to slip the workman in the basin is in danger of being injured; if the rope or the handle of a bucket should give way the workman in the basin is in danger of having the bucket, or its contents, or both, descend upon him; basins contain foul and noxious gases generated in the basin itself or entering the basin from the sewer or elsewhere; these conditions endanger the lives and health of the workmen employed in emptying basins and particu-

larly men obliged to descend into basins. The wearing apparel of all the men employed in basin cleaning is befouled by the muck with which they are obliged to come into contact, particularly the clothing of the men entering the basin; buckets, covered with filthy slime, are placed, after they are hoisted loaded from the basin and before being dumped into the vehicle, and after they are unloaded and awaiting lowering again into the basin, on sidewalks where the filth from the exterior of the buckets trickles down onto the sidewalk to be carried along by the shoes of pedestrians who carry the filth along the streets and into shops, offices and homes.

The present device obviates the necessity of workmen carrying from basin to basin implements now employed in basin cleaning.

Basins need not, as heretofore, be made large enough to give workmen sufficient room to break up material and to shovel material into hand buckets. Not only may basins be made of smaller dimensions than at present, thereby decreasing the initial cost of construction, but heavily loaded trucks passing over a basin will not be so apt to injure a small basin as a larger basin and the expense of keeping basins in repair is diminished.

By my method material entering the basin is caught in the receptacle. One man can empty a basin and can do so in a fraction of the time required for emptying a basin by present methods with several men.

The bottom of the basin may be so constructed as to have a pitch towards the conduit or the bottom of the basin may be constructed as to be convex.

It is obvious that various changes and modifications may be made in the details of construction and design of the above specifically described embodiment of my invention without departing from the spirit thereof.

What is claimed is:—

1. In a sewer, a catch basin mounted in the roadway, a cover for the catch basin having an open central portion, a receptacle having a flanged upper portion seating in the cover portion and removable upwardly therethrough, means carried by said receptacle whereby it may be lifted out of the basin, and a bottom door for the receptacle to admit of dumping the contents thereof.

2. In a sewer, a catch basin, a cover for the catch basin having an open center portion bounded by a conical seat, a receptacle removably received in the basin and adapted to be suspended from said cover, said receptacle having an upper lateral flange with a beveled edge adapted to be received upon said seat, means whereby the receptacle may be lifted out of the basin and out of said cover, and a bottom removable door for the receptacle to admit of dumping the contents.

3. In a sewer, a catch basin, a removable cover therefor having an open center portion

with a seat extending thereabout, a removable receptacle having at its upper portion an outwardly extending flange adapted to be received and supported upon said seat, lateral ports in the side walls of said receptacle, hoods extending inwardly and downwardly above said ports, means whereby the receptacle may be lifted out of the catch basin and out of said cover; and a removable bottom door for the receptacle to admit of dumping the contents.

4. In a sewer, a catch basin, a cover therefor having an open center portion with a seat extending about the opening, a receptacle received in said catch basin downwardly through the opening in said cover and having a flange at its upper portion for engaging the seat on the cover to restrict the downward movement of the receptacle and to suspend the receptacle in the catch basin, means lying within said receptacle for receiving means to elevate and lower the receptacle, and a removable door in the lower portion of the receptacle to admit of dumping the contents of the same.

5. In a sewer, a catch basin, a cover therefor having an open portion with a seat extending thereabout, a receptacle of a diameter to slide through the opening in said cover, said receptacle having an out-turned flange at its upper end for being received upon said seat, a door in the lower portion of the receptacle to admit of dumping the contents, means supported within the receptacle to receive a hoisting means, and a perforated cover received upon said flange.

6. In a sewer construction, a catch basin, a cover therefor having an open portion with a seat thereabout, a receptacle received slidably through the open portion of the cover and having a flange to rest upon said seat to suspend the receptacle in the catch basin, means carried by said receptacle for receiving means to elevate and lower the receptacle, the lower portion of said receptacle having inclined rear and side walls and an opening opposite the rear wall, and a door for normally closing the opening and adapted to admit of dumping the contents of the receptacle.

In testimony whereof I affix my signature.
GEORGE F. EGAN.
